(57) CLAIM

The ornamental design for a TV receiver, as shown and described.

DESCRIPTION

FIG. 1 is a front, right side, perspective view of a TV receiver showing our new design;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a front, right side, perspective view of the TV receiver of FIG. 1, shown in a first environment of use;
FIG. 10 is a front, right side, perspective view of the TV receiver of FIG. 1, shown in a second environment of use; and,
FIG. 11 is a front, right side, perspective view of the TV receiver of FIG. 1, shown in a third environment of use.
Broken lines in FIGS. 9, 10 and 11, illustrate environmental subject matter only and form no part of the claimed design.

1 Claim, 11 Drawing Sheets
